UNITED STATES PATENT OFFICE.

HENRY KASSIK, OF YONKERS, NEW YORK.

RAILWAY-SIGNAL SWITCH.

Application filed April 6, 1925. Serial No. 20,994.

To all whom it may concern:

Be it known that I, HENRY KASSIK, a citizen of the United States, residing at Yonkers, in the county of Westchester and State of New York, have invented certain new and useful Improvements in Railway-Signal Switches, of which the following is a specification.

This invention relates to railway switch signals and particularly to signals for single track roads.

One of the objects of the present invention is to devise a simple and positive signal for street railways of the single track type.

Other objects and advantages will hereinafter appear.

In the accompanying drawings,

Figure 1 is a diagrammatic view showing 20 a stretch of track, and the circuits for the signal lights.

Figure 2 is a front view of a signal box with the front wall removed in the interest of clearness.

Figure 3 is a sectional view of the box shown in Figure 2 taken on the plane indicated by the lines 3—3 of Figure 2 and looking in the direction of the arrows, and also showing a second box placed against the back of the one shown in section.

Figure 4 is a detail view taken on an enlarged scale showing the contact head and its housing and their positions relative to the trolley feed wire.

Figure 5 is a sectional view taken on the plane indicated by the lines 5—5 of Figure 4 and looking in the direction of the arrows.

Referring to the drawings in detail, 40 A—F represents a stretch of single track railway. At suitable intervals along the track are located switches or sidings, two of such sidings indicated as B—C and D—E being illustrated in Figure 1. At such sidings, cars 6 pass each other. The current for propelling said cars 6 is supplied, as is ordinarily the case, from the overhead trolley feed wire 7, which current passes through the car and back through the rails to the source of supply as is common.

At a point opposite each of said sidings or switches is located and mounted in any suitable manner a pair of signal boxes 8 arranged back to back as shown in Figure 3 so that one is facing in a southerly direction and the other in a northerly direction as

viewed from Figure 1. Said boxes 8 are provided with signal lights 9, which lights inform the operator of the car whether to proceed or to stop on the siding until the 60 car coming in the opposite direction passes his car on said siding. The present invention is concerned with the automatic lighting and extinguishing of said lights 9 in the signal boxes 8.

Mounted on the overhead trolley wire 7 at a point adjacent each end of the switch sections and on the branch trolley wires 10 at each end of the sidings is a metal housing 11. As all of the housings 11 with their associated parts are constructed the same, a description of one will suffice for all. Referring particularly to Figures 4 and 5, said housing 11 comprises a metal U-shaped box carried on the rod 12 which is ordinarily used for mounting the trolley ear or member 13 which supports the trolley feed wire 7. Said housing 11 is insulated from the rod 12 and trolley ear 13 by means of the insulated bushing 14 and washer 15, respectively. Secured to the under surface of the top of said housing 11, at one side thereof and adjacent its end, is a metal contact head 16, substantially L-shaped. Said contact head 16 is provided with an off-set portion 17 which bulges inwardly toward the trolley wire 7 or branch wire 10. The head 16 is insulated from the housing 11 by means of the insulated strip 18 placed therebetween, which strip 18 is secured to the housing by 80 means of the screws 19. Said contact head 16 is mounted on said insulated strip 18 by means of the screws 20, surrounding the shanks of which and between the heads of which screws and the surface of the contact head 16 through which said screws 20 pass are spiral springs 21. By reason of this construction, said contact head is capable of yielding from its normal position shown in full lines to the position shown in dotted lines in Figure 5. As will be apparent from Figure 5, the contact head 16 is positioned sufficiently close to the wire 7 and branch wire 10 to permit the trolley wheel of the car which runs along said wires to come into contact with the head 16, which trolley wheel upon coming in contact with said head 16 forces it to yield somewhat thus making a positive contact. The contact head 16 is operatively connected to the lights 9 in the signal boxes 8 as will be explained herein- 100 after.

Inasmuch as all of the signal boxes 8 are similarly constructed a description of one, with particular reference to Figures 2 and 3, will be sufficient. Said box 8 comprises the usual back, front, top and bottom walls, with an opening 22 in the front wall thereof through which the lights 9 are visible, said opening 22 being protected by a screen 23. Secured to the top wall of the box is a porcelain socket member 24 for supporting the lights 9, it being understood that a single light or any number of lights 9 may be used, the drawings showing two. Connected in the usual way to said socket member 24 is a conductor 25 which leads downwardly to a fixed contact post 26 mounted on the rear wall of the box. Mounted on the rear wall of the box and disposed centrally thereof is a flat metal contact plate 27, which is in continuous electrical contact by means of the wire 28 connected thereto. Fixed to said rear wall of the box at a point above said plate 27 is a bracket member 29, its off-setting portion 30 overlying said plate 27 and formed with an opening in its free end. Also fixed to the rear wall on the side of the bracket 29 opposite the contact post 26 is a breaking post 31. Pivotedly mounted on a stud 32 secured to the plate 27, the free end of which stud 32 passes through the opening in the free end of the offset portion 30 of the bracket 29, is a fork member, the prongs 33 of which are adapted to be snapped into engagement with either post 26 or post 31. The handle 34 of said fork member is slotted as at 35. Also pivotally mounted on said stud 32 is a yoke member 36 having an opening in its bottom end. Pivotedly secured to the slotted portion 35 of the handle 34 of the fork member is a pin 37, the free end of which passes through the opening in the bottom end of said yoke member 36. Surrounding said pin 37 is a spiral spring 38, one end of which engages the handle 34 of the fork member and the other end rests against the bottom end of said yoke member 36. Fixed to the rear wall of the box at a point below the contact plate 27 and disposed in a line therewith is a bearing block 39. An elongated metal plate 40 is supported on said block 39 by means of a screw 41 passing through an elongated slot 42 formed in said plate 40, this screw and slot arrangement permitting said plate to take a vertical movement. One end of said plate 40 is connected to the yoke member 36 and the other end is secured to another wooden plate 43 of the same shape. Depending from a hook 44 carried at the end of the plate 43 is a metal contact brush or finger 45. Supported on brackets 46 mounted adjacent the bottom of the box are two sets of magnets 47, two of such magnets comprising a set. Mounted at the top 60 of the top magnet and at the bottom of the

bottom magnet, at their outer ends, are nails 48, which nails are disposed at right angles to the axis of the magnets, and are provided to prevent the finger 45 from clinging to the magnets 47, said finger 45 by reason of said nails immediately returning to its normal or inoperative position which is between the two sets of magnets. 70

As will be apparent from Figure 2, the point around which the fork member and the yoke member pivot and the screw 41 supporting the plate 40 are in alignment so that normally the finger 45 hangs directly in line with said point and screw 41 thereby positioning said finger 45 between the two sets of magnets as hereinbefore stated. Any movement of the fork member and yoke member around their pivot point is against the action of the spring 38. When either set of magnets 47 is energized, said set draws the finger 45 over toward it thereby moving the plate 43, plate 40, yoke 36 and fork member so that one prong 33 of the latter is moved into contact with either post 26 or post 31. When prong 33 of the fork member is in contact with post 26 the circuit for the lights 9 is closed and when the prong 33 is in contact with post 31 said circuit is broken. 80

The circuits (for north traffic) for energizing the sets of magnets 47 for closing the lighting circuit and lighting the lights 9 in the box facing south at switch B-C and the lights 9 in the box facing north at switch D-E are as follows: for the lights 100 in the box facing south at switch B-C; from trolley feed wire 7, trolley wheel, contact head 16, conductor 49, wire 50, magnet 47 and wire 51 which is grounded at 52—for the lights in the box facing north at switch D-E, which lights are arranged in series with the lights in the box facing south at switch B-C; from trolley feed wire 7, through the trolley wheel, contact head 16, conductor 49, wires 53 and 54, magnet 47 110 and wire 55 grounded at 56.

The circuits (for north traffic) for energizing the sets of magnets 47 for putting out the lights 9 in the box facing south at switch B-C and the lights 9 in the box 115 facing north at switch D-E are as follows: for the lights 9 in the box facing north at switch D-E; from trolley feed wire 7, through the trolley wheel, contact head 16, conductor 57, wire 58, magnets 47, wire 55 120 to the ground at 56—for the lights in the box facing south at switch B-C; from trolley feed wire 7, through the trolley wheel, contact head 16, conductor 57, wires 59 and 60, magnets 47, and wire 51 grounded at 52.

The circuits (for north traffic) for energizing the sets of magnets 47 for lighting the lights 9 in the box facing south at switch D-E and for the lights in the box (not 130

shown) facing north at the next succeeding switch along the track (not shown), which latter lights are in series with the lights in the box facing south at switch D—E, are as follows: for the lights 9 in the box facing south at switch D—E; from trolley feed wire 7, through the trolley wheel, contact head 16, conductor 61, wire 62, magnets 47, and wire 55 to the ground at 56;—for the 10 lights in the box (not shown) facing north at the next succeeding switch (not shown); from trolley feed wire 7, through the trolley wheel, contact head 16, conductor 61 and wire 63.

15 For traffic moving in a southerly direction, the circuits for energizing the set of magnets 47 for lighting the signal lights 9 will now be described. The circuits for energizing the sets of magnets 47 for lighting 20 the lights 9 in the box facing north at switch D—E and the lights 9 in the box facing south at switch B—C are as follows: for the lights 9 in the box facing north at switch D—E; from trolley feed wire 7, through 25 branch wire 10, trolley wheel, contact head 16, conductor 67, wire 68, magnets 47 and wire 55 to the ground at 56;—for the lights 9 in the box facing south at switch B—C; from trolley feed wire 7, branch wire 10, 30 trolley wheel, contact head 16, conductor 67, wires 53 and 50, magnets 47 and wire 51 to the ground at 52.

The circuits for energizing the magnets 47 for putting out the lights 9 in the box 35 facing south at switch D—E and for putting out the lights in the box (not shown) facing north in the last preceding switch (not shown) are as follows: for the lights in the box facing south at switch D—E; from trolley feed wire 7, through branch wire 10, trolley wheel, contact head 16, conductor 69, wire 70, magnets 47 and wire 55 to the ground at 56;—for the lights in the box (not shown) in the last preceding switch (not 40 shown); from trolley feed wire 7, through branch wire 10, trolley wheel, contact head 16, conductor 69 and wire 71.

The circuits for energizing the magnets 47 for putting out the lights 9 in the box 45 facing north at switch D—E and the lights 9 in the box facing south at switch B—C are as follows: for the lights 9 in the box facing north at switch D—E; from trolley wire 7, branch wire 10, trolley wheel, contact head 16, conductor 72, wires 59 and 58, magnets 47 and wire 55 to the ground at 56;—for the lights in the box facing south at switch B—C; from trolley wire 7, branch wire 10, trolley wheel, contact head 16, conductor 72, wire 60, magnets 47 and wire 51 to the ground at 52.

The circuits for energizing the magnets 47 for lighting the lights 9 in the box facing north at switch B—C, and for the lights in 55 the box (not shown) facing south in the next

succeeding switch (not shown) are as follows: for the lights in the box facing north at switch B—C; from trolley wire 7, through branch wire 10, trolley wheel, contact head 16, conductor 73, wire 74, magnets 47 and wire 51 to the ground at 52;—for the lights in the box (not shown) facing south in the next succeeding switch (not shown); trolley wire 7, branch wire 10, trolley wheel, contact head 16, conductor 73 and wire 75.

Strung along the track for its entire length and connected to a source of power not shown is a lighting wire 76. Leading from said wire 76 to the lights 9 in each box 8 is a branch wire 77, and leading from the lights 9 to the contact post 26 is a wire 25. The circuit for the lights 9 is as follows: from wire 76, through branch wire 77, lights 9, wire 25, contact post 26, through prong 33 of the fork member, stud 32, plate 27 and wire 28 to the ground. As will be understood, when the fork member is moved so that its prong 33 is snapped into engagement with the contact post 26 the circuit for the lights 9 is closed, and when the prong 33 of said fork member comes into engagement with post 31 the circuit is broken.

Referring to Figure 1, the operation of the system is as follows: As the car 6 is about to leave the switch B—C, as illustrated, its trolley wheel comes in contact with the contact head 16 in the housing 11. As hereinbefore explained, this causes current to flow from the trolley feed wire 7, through the trolley wheel, contact head 16, conductor 49, wire 50, magnets 47 and wire 51 to the ground. This causes the energization of magnets 47 which draws the finger 45 toward that particular set of magnets. The drawing of the finger 45 over toward the magnets moves the fork member so that its prong 33 comes into contact with the post 26, thus closing the circuit over which the current for the lights 9 flows, and lighting the lights 9 in the box facing south at switch B—C.

Current also flows simultaneously from conductor 49 through wire 53 to the magnets 47 for lighting the lights 9 in the box facing north at switch D—E, thus simultaneously lighting said lights. As the car proceeds to the next switch D—E, its trolley wheel comes into contact with the contact head 16 in the housing 11 located at the beginning of the switch D—E. Current then flows from the trolley feed wire 7, through the trolley wheel, contact head 16, conductor 57, wire 58, magnets 47 and wire 55 to the ground putting out the lights in the box facing north at switch D—E.

At the same time current also flows from conductor 57, through wire 59 and wire 60, magnets 47 and wire 51 to the ground putting out the lights in the box facing south at switch B—C. The operation of the sys-

tem when a car is moving in a southerly direction is the same.

It will be understood that the ordinary means for reducing the current in the feed wire 7 before using the same for lighting the lights and energizing the magnets 47 will be provided.

Variations may be resorted to within the scope of the invention and portions of the 10 improvements may be used without others.

I claim:

1. In a railway signal switch, in combination with the trolley wheel of a car, a signal box including signal lights, a circuit for lighting said lights, a contact plate mounted in said box and connected to one conductor of said lighting circuit, a contact post carried by said box and connected to the other conductor of said lighting circuit, 20 a breaking post carried by said box and oppositely disposed to said contact post, a movable fork member mounted on said contact plate and in continuous engagement therewith, means carried by said box for moving said fork member into engagement with said contact post or said breaking post for making or breaking said lighting circuit, respectively, and means cooperating with said trolley wheel for controlling said last 30 mentioned means.

2. In a railway signal switch, in combination with the trolley wheel of a car, a signal box including signal lights, a circuit for lighting said lights, a contact plate mounted 35 in said box and connected to one conductor of said lighting circuit, a contact post carried by said box and connected to the other conductor of said lighting circuit, a movable fork member mounted on said contact plate and in continuous engagement therewith, sets of magnets mounted in said box and disposed in spaced relationship, connections between the fork member and the sets of magnets, said connections adapted to 45 be moved by said sets of magnets upon energization of the latter, and means cooperating with said trolley wheel for energizing said sets of magnets.

3. In a railway signal switch, in combination with the trolley wheel of a car, a signal box including signal lights, a circuit for lighting said lights, a contact plate mounted in said box and connected to one conductor of said lighting circuit, a contact 50 post carried by said box and connected to the other conductor of said lighting circuit, a movable fork member mounted on said contact plate and in continuous engagement therewith, sets of magnets mounted in said box and disposed in spaced relationship, connections between the fork member and the sets of magnets, said connections adapted to be moved by said sets of magnets upon energization of the latter and means for energizing said magnets said means com-

prising a contact head mounted on the overhead trolley wire and in the path of movement of the trolley wheel of said car whereby a contact is established.

4. In a railway signal switch, in combination with the trolley wheel of a car, a signal box including signal lights, a circuit for lighting said lights, a contact plate mounted in said box and connected to one conductor of said lighting circuit, a contact post carried by said box and connected to the other conductor of said lighting circuit, a breaking post mounted in said box, a fork member pivotally mounted on said contact plate and in continuous engagement therewith, one of the prongs of said fork member being adapted to engage either said contact post or said breaking post, means for normally holding the prong in engagement with either said contact post or said breaking post, means carried by said box for moving said fork member into engagement with either said contact post or said breaking post for making or breaking said lighting circuit, respectively, and means operating with said trolley wheel for controlling said last mentioned means.

5. In a railway signal switch, in combination with the trolley wheel of a car, a signal box including signal lights, a circuit for lighting said lights, a contact plate mounted in said box and connected to one conductor of said lighting circuit, a contact post carried by said box and connected to the other conductor of said lighting circuit, a breaking post mounted on said box, a fork member pivotally mounted on said contact plate and in continuous engagement therewith, one of the prongs of said fork member adapted to engage either said contact post or said breaking post, a spiral spring capable of pressing against the handle portion of said fork member to hold one prong thereof normally in engagement with either said contact post or said breaking post, means carried by said box for moving said fork member against the action of said spiral spring into engagement with either said contact post or said breaking post for making or breaking said lighting circuit, respectively, and means cooperating with said trolley wheel for controlling said last mentioned means.

6. In a railway signal switch, in combination with the trolley wheel of a car, a signal box including signal lights, a circuit for lighting said lights, a contact plate mounted in said box and connected to one conductor of said lighting circuit, a contact post carried by said box and connected to the other conductor of said lighting circuit, a breaking post mounted on said box, a fork member pivotally mounted on said contact plate and in continuous engagement therewith, one of the prongs of said fork member

- adapted to engage either said contact post or said breaking post, a spiral spring capable of pressing against the handle portion of said fork member to hold one prong 5 thereof normally in engagement with either said contact post or said breaking post, a contact finger operatively connected to said fork member, sets of magnets mounted in said box and disposed at either side of said 10 contact finger, said magnets capable of drawing said contact finger to either side of the pivot point of said fork member whereby said fork member is moved against the action of said spiral spring into engagement with 15 either the contact post or the breaking post, respectively, upon the energization of the magnets, and means cooperating with said trolley wheel for energizing said sets of magnets.
- 20 7. In a railway signal switch, in combination with the trolley wheel of a car, a signal box including signal lights, a circuit for lighting said lights, a contact plate mounted in said box and connected to one conductor of said lighting circuit, a contact post carried by said box and connected to the other conductor of said lighting circuit, a breaking post mounted on said box, a fork member pivotally mounted on said contact 25 plate and in continuous engagement therewith, one of the prongs of said fork member adapted to engage either said contact post or said breaking post, a spiral spring pressing against the handle portion of said fork member to normally hold said fork member in 30 engagement with either said contact post or said breaking post, sets of magnets mounted in said box, connections between said fork member and said magnets for rocking said fork member about its pivot point, said connections including a yoke member pivotally mounted on said contact plate and adapted to cooperate with the handle portion of said fork member, an elongated plate connected to said yoke member, a wooden plate fixed 35 to said elongated plate and a contact finger carried by said wooden plate, said contact finger being normally disposed between said sets of magnets and capable of being drawn toward either set of magnets upon their 40 energization for rocking said fork member, a circuit for energizing said sets of magnets and means cooperating with said trolley wheel for closing said circuit.
- 45 In testimony whereof, I hereunto affix 50 my signature.

HENRY KASSIK.
